William L. Sanderson

Design for Cook-Stoves

U.S. PATENT OFFICE
Cooking Stoves

DES. 296

Patented June 25, 1850

44-296

DESIGNS:
Stoves and Furnaces,
Cooking Stoves and Ranges

Des. 296

Wm L. Sanderson, of Troy N. Y.,
Letters Patent No. 296. Dated June 25. 1850

The Schedule referred to in these Letters Patent and
making part of the same.

To all to whom these presents shall come:

Be it known that I,
Wm L. Sanderson, of Troy, in the County of Rensselaer,
and State of New York, have invented or produced
a new design of Cook Stove which I call "the gem
of Troy", and I do hereby declare that the following
is a full, clear and exact description of the same,
reference being had to the annexed drawings, making
a part of this specification, in which fig. 1, is a
view of the front plate of the stove, and fig. 2,
a side elevation of the whole stove, the summer
stove or hearth being detached and not represented.

My stove is in the usual form of the square
four boiler hole; the ornaments consist of represen-
tations of oak leaves and acorns disposed on
the doors, panels and other parts of the stove,
as represented.

What I claim and desire to secure
by letters patent is the design and configuration
of cook stove as herein described and represented

Ms. 296

in the annexed drawings.
